Application January 16, 1936, Serial No. 59,379

18 Claims. (Cl. 200—151)

This application relates to contact arrangements for switches and more specifically relates to multiple break contact arrangements.

For an understanding of the switch contact arrangements herein disclosed reference should be had to the appended drawing disclosing the same.

In this drawing, Figs. 1 and 2 are sections as if on line 1—1 of Fig. 3 showing the switch parts 10 in on and off positions respectively.

Fig. 3 is a side elevation.

It will be seen that the contact arrangement herein disclosed includes an insulating base 10 upon which are mounted spaced stationary contacts 11 having conductor terminal binding posts 12. For engaging each of the stationary contacts there is provided, within a slide 15 formed as part of an insulation housing 16, a movable contact 35 formed to engage the contacts with a butt 20 pressure and with a wiping contact engagement.

In addition the housing 16 is shown as provided with a U-shaped contact spring 36 having contact tips 37. The spring 36 functions to urge the tips of the stationary contacts 11 towards 25 each other and thus increase the butt contact pressure of them on contact 35 and to urge contact tips 37 tightly into engagement with the stationary contacts 11; contact tips 37 provide arcing tips; it being observed that contacts 37 30 make with stationary contacts 11 before and break therefrom after the movable contact 35 makes and breaks contact with contacts 11.

The housing 16 is adapted to be reciprocated by means not shown for make and break.

It will be observed that the edges of the openings in the bottom wall of the housing 16 on the opposite sides of the blade 15 through which contacts 11 pass are dimensioned to fit closely around the stationary contacts 11 so that the interior of the housing is sealed at all times by the stationary contacts 11.

Now having described the switching contact arrangement herein disclosed, reference will be had to the following claims for a determination of the inventions claimed.

We claim:

1. A switch including two adjacent stationary contacts, an insulation blade movable between 50 and in substantially wiping engagement with them and provided with a contact positioned to engage and wipe a part of each stationary contact, the blade also carrying a second movable contact in the form of a U-shaped spring, electrically connected to the first blade contact and 55

positioned to engage, wipe, and embrace the stationary contacts.

2. A switch including two adjacent stationary contacts, an insulation blade movable between 5 and in substantially wiping engagement with them and provided with a contact positioned between the adjacent stationary contacts to engage and wipe them, the blade also carrying a second contact electrically connected to the first blade contact and adapted to engage and wipe the 10 stationary contacts independently of the engagement between them and the first blade contact.

3. A switch including two adjacent stationary contacts, an insulation blade movable between 15 and in substantially wiping engagement with them and provided with a contact positioned between the adjacent stationary contacts to engage and wipe them, the blade also carrying a second contact electrically connected to the first blade contact and adapted to engage and wipe the 20 stationary contacts independently of the engagement between them and the first blade contact, the second blade contact being U-shaped and formed to embrace the stationary contacts.

4. A switch including two adjacent stationary 25 contacts, an insulation blade movable between and in substantially wiping engagement with them and provided with a contact positioned to engage and wipe a part of each stationary contact, the blade also carrying a second movable 30 contact in the form of a U-shaped spring, electrically connected to the first blade contact and positioned to engage, wipe, and embrace the stationary contacts, the blade and its contacts being enclosed within a hollow housing having 35 openings on opposed sides of the blade receiving the stationary contacts.

5. A switch including two adjacent stationary contacts, an insulation blade movable between 40 and in substantially wiping engagement with them and provided with a contact positioned between the adjacent stationary contacts to engage and wipe them, the blade also carrying a second contact electrically connected to the first blade contact and adapted to engage and wipe 45 the stationary contacts independently of the engagement between them and the first blade contact, the blade and its contacts being enclosed within a hollow housing having openings on opposed sides of the blade receiving the stationary 50 contacts.

6. A switch including two adjacent stationary contacts, an insulation blade movable between 45 and in substantially wiping engagement with them and provided with a contact positioned be- 55

of the openings being dimensioned to fit close around the stationary contacts.

18. A switch including two adjacent stationary contacts, an insulation blade movable between 5 and in substantial wiping engagement with them and provided with a contact positioned between the adjacent stationary contacts to engage and wipe them, the blade also carrying a second contact adapted to engage and wipe the stationary 10 contacts independently of the engagement be-

tween them and the first blade contact, the second blade contact being U-shaped and formed to embrace the stationary contacts, the blade and its contacts being enclosed within a hollow housing having openings on opposed sides of the blade receiving the stationary contacts, the edges of the openings being dimensioned to fit close around the stationary contacts. 5
